PRICE TAG

Robert J. Slavsky, Detroit, Mich., assignor to Shaw & Slavsky, Inc., Detroit, Mich.

Filed Dec. 15, 1966, Ser. No. 5,050

Term of patent 14 years

(Cl. D1—3)

FIG. 1

FIG. 1 is a front elevational view of a price tag showing my design.

FIG. 2 is a side elevational view thereof.

The dominant features of my design reside in the portions shown in full lines, it being understood that the numerals shown in FIG. 1 are for purposes of illustration only and that the surface shading designates areas of contrasting color.

I claim:

The ornamental design for a price tag, substantially as shown and described.
